UNITED STATES PATENT OFFICE.

JOHN HENDERSON, OF WATERBURY, CONNECTICUT.

STEAM-HEATED TUMBLING-BARREL.

1,099,041.

Specification of Letters Patent.

Patented June 2, 1914.

Application filed February 18, 1913. Serial No. 749,270.

To all whom it may concern:

Be it known that I, JOHN HENDERSON, a citizen of the United States, residing at Waterbury, in the county of New Haven and State of Connecticut, have invented a new and useful Improvement in Steam-Heated Tumbling-Barrels, of which the following is a specification.

This invention relates generally to tumbling barrels and more particularly to a tiltable rotary barrel, and the object of the invention is to provide a steam jacket in connection with a tumbling barrel of this kind for the purpose of heating the contents of said barrels.

Another object of the invention is to provide for the introduction of steam during the operation of the tumbling barrel and at the same time eliminate back pressure.

Another object of the invention is to provide a steam heated tumbling barrel in which live steam is introduced and from which water of condensation is discharged at definite intervals.

With these objects in view the invention consists in the novel features of construction, combination and arrangement all of which will be fully described hereinafter and pointed out in the claims.

In the drawings forming a part of this specification: Figure 1 is a perspective view of a tumbling barrel embodying my invention, a portion of the barrel being broken away. Fig. 2 is a vertical sectional view taken through the barrel and a hollow shaft extending into the bottom of the same. Fig. 3 is a face view of the inner side of the bottom plate and showing the construction and arrangement of the collecting scoop for collecting and discharging the water of condensation. Fig. 4 is a detail end view. Fig. 5 is a detail sectional view showing the manner of connecting the steam pipe to the end of a hollow shaft. Fig. 6 is a detail view of the collar and discharge pipe, and Fig. 7 is a plan view of the collar.

In carrying out my invention I employ a tumbling barrel A, having the usual construction of bottom A', said bottom being usually flanged as shown in Fig. 2 and rigidly attached to the said flanged bottom is a supplemental bottom or plate B providing a closed circular space at the rear or bottom end of the tumbling barrel. The barrel is provided with the usual construction of bevel gear C and rocks upon a trun-

nion D, it being understood that the barrel is both rotatable and tiltable and in the drawings I have illustrated means for raising and lowering the barrel, but no claim is made thereto in this application. A hollow shaft E is passed centrally through the hub of the gear C and communicates at its inner end with the closed space at the bottom of the tumbling barrel.

F, indicates a steam pipe which is connected to the trunnion D, said trunnion being made hollow so that steam can be introduced thereto and a steam pipe G leads from this hollow trunnion to the rear end of the hollow shaft E, said steam pipe being connected to said hollow shaft through the medium of a coupling member G', which enters the rear end of the hollow shaft and is held in place by means of a gasket H, secured by means of screws H', a packing H² being interposed between the shaft and coupling connection and a similar arrangement may be employed where the steam pipe enters the hollow trunnion, this construction making these joints steam tight. Instead of a separate coupling G' as shown in Fig. 1 it is obvious that the rear end of pipe G can be bent or shaped so as to enter the rear end of the hollow shaft and the gasket and packing will be exactly the same as previously described. The steam pipe F is provided with a valve F' and a discharge cock F² can be connected therewith if desired.

When the valve F' is opened steam will pass through the pipe F through the hollow trunnion, pipe G and hollow shaft into the closed space or steam jacket at the bottom or rear end of the tumbling barrel thereby thoroughly heating the contents of said barrel and by the employment of the hollow trunnion and shaft and making the steam communications in the manner heretofore described it is obvious that steam can be introduced during both the rotating and tilting operations of the barrel. A portion of the steam will in due time be condensed and in order to remove this water of condensation I provide a combined collecting and discharging scoop I, comprising the curved or circumferential member I', which is in the nature of a tube attached to the inner face of the bottom or plate B, and the radial member I² which extends from the circumferential member I nearly to the plate B. This collecting scoop composed of the mem-

bers I' and I² is connected to the plate B by means of suitable clips such as shown at I³. The inner end of the radial member I² communicates with an opening B² produced in 5 the plate B, which opening in turn communicates with a passage or bore K produced in the hub of the gear C, said passage or bore K being of the shape indicated in Fig. 2 and thereby providing a discharge outlet for 10 the water of condensation, which is collected in the member I' at each rotation of the barrel and conveyed through the member I² to the opening B² and passage K and surrounding the hub of the gear is a collar L 15 having an opening M which opening is adapted to register with the passage or opening K once at each revolution of the barrel so that the water of condensation can be discharged through said opening M into the 20 curved pipe N which leads therefrom, said pipe extending downwardly toward the floor where the water can be discharged. The collar L serves as a cut-off to close the opening K during the remaining portion of the revolution. 25 This collar L is formed with an inwardly extending flange L' which snugly fits the hub of the gear and prevents the escape of any of the water. The steam jacket is provided with a blow-off cock A², which 30 is usually opened when the device is first started.

In operation the tumbling barrel is supported and operated the same as tumbling barrels in general use and during such operations steam is conveyed to the steam jacket at the bottom or rear end thereof through 35 the pipe F, hollow trunnion D, pipe G and hollow shaft E. The steam entering the jacket quickly heats the contents of the barrel and inasmuch as the barrel is rotating it will be understood that any water of condensation accumulating in the bottom portion of the steam jacket will be scooped up in the 40 curved circumferential member I' and carried into the radial member I² upon the upward turn thereof and this water of condensation is discharged through the opening or passage K produced in the hub and the 45 parts are so positioned with reference to the collar L having the opening N that once at 50 each revolution the water collected or scooped from the lower portion of the steam

jacket will be discharged through the pipe N and during the balance of the revolution the discharge openings are cut-off. 55

By means of a steam heated tumbling barrel constructed as herein shown and described I am enabled to heat the contents of the tumbling barrel while being operated upon and at the same time I eliminate the 60 back pressure.

It will thus be seen that I provide a simple and efficient improvement capable of carrying out all of the objects hereinbefore referred to. 65

What I claim is:—

1. A tiltable rotary tumbling barrel having a steam jacket, a collector arranged in said jacket, a hollow shaft leading into said jacket, a gear mounted upon said shaft, the hub thereof having an opening communicating with said collector, a collar surrounding said hub, and having an opening therein adapted to register intermittently with the said opening in the hub, a hollow trunnion and steam connection for said trunnion and hollow shaft as set forth. 70

2. A tiltable rotary tumbling barrel having a steam jacket, a collector arranged in said jacket, a hollow shaft leading into said jacket, a gear attached to said barrel, and mounted upon said shaft, the hub of said gear having an opening communicating with said collector, steam connections for the shaft to supply live steam, and means connected with said gear for carrying off the 80 water of condensation. 85

3. A tiltable rotary tumbling barrel having a steam jacket, a collector arranged in said jacket, a hollow shaft leading into said jacket, a gear attached to bottom of barrel and mounted upon said shaft, said gear having a passage in its hub communicating with the inner end of said collector, a collar surrounding said hub, said collar having a single opening through which condensed steam escapes, and steam connections for supplying the hollow shaft with live steam as set forth. 90 95

JOHN HENDERSON.
